UNITED STATES PATENT OFFICE.

SUMNER A. BEMIS, OF SPRINGFIELD, MASSACHUSETTS, AND LOUIS PFINGST,
OF NEW YORK, N. Y.

RAILWAY.

SPECIFICATION forming part of Letters Patent No. 398,687, dated February 26, 1889.

Application filed June 30, 1888. Serial No. 278,671. (No model.)

To all whom it may concern.

Be it known that we, SUMNER A. BEMIS and LOUIS PFINGST, citizens of the United States of America, residing, respectively, at Springfield, in the county of Hampden and State of Massachusetts, and the city, county, and State of New York, have invented new and useful Improvements in Railways, of which the following is a specification.

10 The present invention relates to improved railways, and particularly to the construction and combination of the track-rails and supporting-chairs therefor.

Reference is to be had to the accompanying drawings, forming part of this specification, in which the present invention is illustrated, and in which similar characters of reference indicate corresponding parts in all the views.

Figure 1 is a perspective view of a chair, 20 together with a portion of a track-rail and the wedge or confining blocks therein. Fig. 2 is a side view of the chair and a portion of two rails confined therein; and Fig. 3 is a cross-section on line 3 3, Fig. 2.

25 The track-rails A rest in the chairs H, which are by their bases d secured in any approved manner to suitable cross-ties or supports, b, therefor, and, as shown, the rail is below its tread-surface x at each side provided with 30 concaved or inwardly and downwardly converging walls y, in farther downward continuation of which are vertical walls, forming the surface of the mid-rib j.

The chairs H consist of opposing trough-shaped walls open at their ends and top, each wall at and from the base being for a short distance vertical, as shown at 12, and upwardly and outwardly inclining, as at 13. Blocks of 35 wood or other suitable material, 15, are disposed in the bottom of the chairs between the said vertical walls 12, and on said blocks the bottoms of the mid-ribs of the rails A rest.

Blocks K, each provided with a vertical wall, 16, to fit the side of the rail mid-rib j, 40 terminating in the convexed upper face, 17, to fit the concavity y of the rail under its tread, and having its opposite side, 18, inclined to correspond with the inclining side wall of the chair, are, together with said rail, placed 45 within the inclining walls of the chair, and

when so in place the enlarged overlying top of the rail prevents the wedges rising in the chair to loosen their bind upon the rail or to permit any lateral play thereof; the rail being firmly held against rising by the provision of 55 the angular dogs L, each consisting of the lug 20, which passes through an aperture, 21, in the rail mid-rib, and the shank 22, which passes through a hole in the chair-base d and through the supporting cross-tie, receiving at its screw-threaded lower end a nut, 23, to be turned 60 against the underside of the said tie, by which it is constrained to its confining position upon the rail A.

The wedge-shaped blocks K are provided 65 at their ends with flanges z to lie outside of and against the end walls of the chair, whereby the said blocks are held against longitudinal movement in either direction.

If desired, in lieu of the removable wooden 70 block between the vertical lower walls of the chair, the inclined walls 13 may extend to the base of the chair and the rail rest directly on said base; but it is preferred to follow the construction shown, as by the use of the blocks 75 15 a better bed for the support of the rail is secured, jarring and rattling being in a considerable degree obviated.

The chair may in some instances be so supported that the nuts 23, screwing on the shanks 80 22 of the angular dogs L, may bear directly against the base-plate of the chair, instead of against the under side of the tie or other chair-support; but it is preferred to have the said shanks pass through said tie and to have 85 the nuts bear against the under side thereof, said tie or chair-support, however, being and forming, when the chair is confined thereon, a part of the base of the chair, and so far as is concerned the confining effect of the rail 90 within the chair by the said dogs L, substantially as described, the above-mentioned relative disposition of the nuts is immaterial.

What we claim as our invention is—

1. The combination, with the chairs, each 95 comprising the base and the opposing inclined walls 13 13, of the track-rails having the enlarged upper tread and narrower mid-rib j, provided with the apertures 21, the wedge-blocks K, the confining-dogs L, each compris- 100

ing the lug 20, entering one of said rail-apertures, and the screw-threaded shank 22, passing vertically through said base, and the nuts 23, substantially as and for the purpose described.

2. The combination, with the chairs, each comprising the base and the opposing inclined walls 13 13, of the track-rails having the enlarged upper tread and narrower mid-rib *j*, provided with the apertures 21, the wedge-blocks *K*, provided at each end with the outwardly-extended flanges *z*, the confining-dogs *L*, each comprising the lug 20, entering one of said rail-apertures, and the screw-threaded shank 22, passing vertically through said base, and the nuts 23, all substantially as shown, and for the purpose described.

3. The combination, with the chairs, each comprising the base and the opposing inclined walls 13 13, and the blocks 15, resting on the said base, of the track-rails having the enlarged tread and narrower mid-rib *j*, resting on said blocks 15 and provided with the apertures 21, the wedge-blocks *K*, the confining-dogs *L*, each comprising the lug 20, entering one of said rail-apertures, and the screw-threaded shank 22, passing vertically through said base, and the nuts 23, substantially as described.

SUMNER A. BEMIS.
LOUIS PFINGST.
